UNITED STATES PATENT OFFICE.

JAMES LESLIE DONALY, OF NEWARK, NEW JERSEY, ASSIGNOR OF ONE-HALF TO SHEPARD M. MILLS, OF SAME PLACE.

DESIGN FOR A PUZZLE-BOX.

SPECIFICATION forming part of Design No. 26,530, dated January 12, 1897.

Application filed December 10, 1896. Serial No. 615,216. Term of patent 3½ years.

To all whom it may concern:

Be it known that I, JAMES LESLIE DONALY, a citizen of the United States, residing at Newark, in the county of Essex and State of New Jersey, have invented and produced a Design for Puzzle Boxes or Cases, of which the following is a specification, reference being had to the accompanying drawings, which form a part thereof.

10 In the drawings forming part of this specification, Figure 1 is a plan view of my improved puzzle box or case, and Fig. 2 a transverse section thereof on the line 2-2, these two views being deemed necessary to fully 15 illustrate my design.

The leading feature of my design consists of a rectangular box or casing which is oblong in form and which consists of a bottom 5, vertical side walls 6, and end walls 7.

20 The bottom of the box or casing is concave on its upper surface, as clearly shown in Fig. 2, and the upper surface of said bottom is provided with four parallel vertical walls 8, 9, 10, and 11, whereby five similar longitudinal spaces 12 are formed, and the vertical walls 8, 9, 10, and 11 terminate at each end a short distance from the end walls of the box or casing, whereby transverse spaces 13 are formed.

25 The vertical side wall 8 is provided adjacent to the middle thereof with an opening or passage 14, at each side of which are segmental outwardly-curved walls 15, whereby a space 16 is formed, which is closed at its outer 30 side by the adjacent side wall 6, and the walls

9 and 10 are provided with similar passages or openings 17, at the opposite sides of which are segmental walls 18, by which the corresponding ends of the walls 9 and 10 are connected at each side of the passages or openings 17, the walls 18 being outwardly curved, and the longitudinal vertical wall 11 is also provided with a passage or opening 19, at each side of which are transverse segmental walls 20, which connect with the adjacent side walls 45 6 of the box or casing, whereby a space 21 is formed, the outer side of which is closed, and by means of the segmental walls 18 a similar space 22 is formed, which is open at both sides.

The entire design is symmetrical in form, 50 and it will be observed that the longitudinal spaces 12 are all of the same width and that the transverse spaces 13 are similar in width and communicate with the longitudinal spaces 12 and that all of said spaces and the 55 spaces formed by the segmental walls 15, 18, and 20 are in communication.

Having fully described my new and original design, I claim as new and desire to secure by Letters Patent—

The design for a puzzle box or case herein shown and described.

In testimony that I claim the foregoing as my invention I have signed my name, in presence of the subscribing witnesses, this 7th day 65 of December, 1896.

JAMES LESLIE DONALY.
